(57) CLAIM

The ornamental design for a LED bulb, as shown and described.

DESCRIPTION

FIG. 1 is a perspective view of a first embodiment of an LED bulb;

FIG. 2 is a front view of the LED bulb depicted in FIG. 1;
FIG. 3 is a left side view of the LED bulb depicted in FIG. 1;

FIG. 4 is a top view of the LED bulb depicted in FIG. 1;
FIG. 5 is a bottom view of the LED bulb depicted in FIG. 1;

FIG. 6 is a perspective view of a second embodiment of an LED bulb;

FIG. 7 is a front view of the LED bulb depicted in FIG. 6;
FIG. 8 is a left side view of the LED bulb depicted in FIG. 6;

FIG. 9 is a top view of the LED bulb depicted in FIG. 6; and,
FIG. 10 is a bottom view of the LED bulb depicted in FIG. 6.

The broken lines showing in the figures are for illustrative purposes only and form no part of the claimed design.
